UNITED STATES PATENT OFFICE.

ALBERT B. WEISSENBORN, OF APPLETON, WISCONSIN.

SHUTTLE.

1,119,132.

Specification of Letters Patent.

Patented Dec. 1, 1914.

Application filed February 5, 1912. Serial No. 675,408.

To all whom it may concern:

Be it known that I, ALBERT B. WEISSENBORN, a citizen of the United States, and resident of Appleton, in the county of Outagamie and State of Wisconsin, have invented new and useful Improvements in Shuttles, of which the following is a description, reference being had to the accompanying drawings, which are a part of this specification.

This invention relates to shuttles for wire weaving and has for its object to provide a double set of supporting rollers on which the shuttle travels, one roller of each set being movable vertically at the end of the travel of the shuttle whereby the shuttle travels on one set of rollers in traveling in one direction and on the other set of rollers in traveling in the other direction.

Another object of the invention is to give to the rollers of the two sets a different angularity with relation to the direction of travel of the shuttle whereby the shuttle will have a tendency to travel close to the reed in either direction of travel thereof.

With the above and other objects in view the invention consists in the shuttle for wire weaving as herein claimed, and all equivalents.

Referring to the accompanying drawings in which like characters of reference indicate the same parts in the different views: Figure 1 is a plan view of a shuttle constructed in accordance with this invention; Fig. 2 is a bottom view thereof; Fig. 3 is a sectional side elevation thereof; Fig. 4 is a detail sectional view of one end thereof; and, Fig. 5 is a transverse sectional view through the detent for the swinging bobbin carrier.

In these drawings 10 indicates a shuttle body having a central opening in which a swinging bobbin carrier 11 is pivotally mounted at 12 to be capable of reversing the position of the bobbin at each end of the travel of the shuttle, said bobbin carrier 11 having an arm 13 carrying a guide eye 14 for the wire 15 let off from the bobbin 16 and adapted to enter slots at the ends of the central opening of the shuttle and strike against stop plates 17 to limit the throw of the bobbin carrier. In each of these slots is a spring pressed detent pin 18 which is engaged by the arm 13 and said arm has beveled notches 19 at its edges to force the detent pin back when the arm enters the slot

and also has a shallow recess 20 at its middle portion to be engaged by the detent for securely holding the shuttle carrier in either of its operative positions. Besides the central opening the shuttle is provided with recesses on its under surface at each end thereof and in these recesses are pivotally mounted C-shaped swinging frames 21 by means of trunnion screws 22 threaded through the sides of the shuttle and entering sockets provided for them as shown in Fig. 4. These frames 21 form swinging roller frames which are adapted to be engaged by the end of the arm 13 and swung against the pressure of springs 23 to lower their free ends. Between these free ends of the roller frames 21 are mounted rollers 24 which may for convenience be formed of two roller sections, one having a screw 26 embedded in it and projecting therefrom to form one trunnion bearing while the other is threaded on the end of said screw and carries a trunnion plate 27 to form the other trunnion bearing for the roller. With this construction the two trunnion bearings are adjustable toward or away from each other by turning one roller section with relation to the other and this allows of the roller being conveniently mounted in the arms of the swinging frames 21. A jam nut 28 is threaded on the screw 26 to bear against the adjustable roller member and lock it in its adjustment on the screw and the other roller member is preferably provided with a recess to receive said jam nut. This roller 24 is desirably set with its axis at right angles to the axis of the shuttle proper or the line of direction of travel of the shuttle and by the swinging movements of the roller frame 21 is raised or lowered with relation to the shuttle, its lower position, as shown in Fig. 3, being occupied when the arm 13 is in engagement with its frame 21. Each of the recesses at the end of the shuttle is also provided with an angular fixed roller 29, that is, its axis is at an angle to the axis or the line of direction of travel of the shuttle proper and is immovable vertically or otherwise and these fixed rollers at the two ends of the shuttle are set at opposite angles so that when either of them is in bearing on the shuttle board, which as will be later seen is only when the shuttle moves with it in advance, such angularity causes it to lead the shuttle toward the reed and thus prevent the shuttle straying from its proper course.

In either position of the bobbin carrier 11 its arm 13 engages one of the swinging frames 21 to hold the roller thereof at its lower position which is lower than the fixed roller at that end of the shuttle and the other roller 24 on the swinging frame which is not engaged by the arm 13 is in its upper position which is higher than the fixed roller at that end of the shuttle. Thus the shuttle is always resting upon the fixed oblique roller 29 at the front end thereof and upon the vertically movable transverse roller 24 at the rear end thereof, and at the end of the travel of the shuttle in one direction, the reversal of the position of the bobbin carrier causes the reversal of the positions of the adjustable rollers so that this condition of the shuttle traveling on its oblique fixed roller at its front end and its transverse vertical adjustable roller at its rear end is maintained. The change in position of the bobbin carrier may be accomplished by hand or mechanically, the spring pressed detent pin 18 yielding to permit thereof.

What I claim as new and desire to secure by Letters Patent is:

1. A shuttle, comprising a shuttle body provided with a pair of rollers at each end, one of the rollers of each pair being set at an oblique position, and means for moving one of the rollers of each pair vertically to cause it to take a position higher or lower than the other roller of the pair.
2. A shuttle, comprising a shuttle body, a pair of supporting rollers at each end thereof, one roller of each pair being oblique to the shuttle and the oblique rollers having their angularity of position in opposite directions, and one of the rollers of each pair being mounted to have a vertical adjustment to assume a position higher than the other roller of the pair or to assume a position lower than the other roller of the pair,
3. A shuttle, comprising a shuttle body, a pair of rollers at each end of the shuttle body, one of the rollers of each pair having an oblique position with relation to the shuttle body, a frame pivotally mounted at each end of the shuttle body, one of the rollers at that end of the shuttle body being mounted therein and adapted by the pivotal move-

ments of the frame to have a vertical adjustment to permit it to stand lower than the other roller of the pair or higher than the other roller of the pair, and means for swinging the frames.

4. A shuttle, comprising a shuttle body, a swinging frame at each end thereof, a pair of rollers at each end of the shuttle body, one of which is journaled in the shuttle body and the other is journaled in the swinging frame to be moved by the swinging frame higher than or lower than the roller journaled in the shuttle body, a bobbin carrier pivotally mounted on the shuttle body and adapted to have its position reversed at the end of travel of the shuttle in either direction, and an arm on the bobbin carrier adapted to engage the swinging frames for changing their positions.

5. A shuttle, comprising a shuttle body, a swinging frame pivotally mounted at each end thereof, a pair of rollers at each end of the shuttle body, one of which is journaled in the shuttle body and the other is journaled in the swinging frame to be moved thereby higher than or lower than the other roller of the pair, a spring bearing on each of the swinging frames, a bobbin carrier pivotally mounted in a central opening of the shuttle body and adapted to have its position reversed at the end of travel of the shuttle in either direction, an arm on the bobbin carrier adapted to engage and move the swinging frames against the action of their springs, and a spring detent for engaging and holding the bobbin carrier in either position thereof.

6. A roller support for the ends of shuttles, comprising a roller fixed in position, a frame having fixed opposite bearings, a roller journaled in the bearings comprising a pair of roller members, a screw fixed in one roller member and forming a trunnion therefor, the other roller member being adjustably threaded on the screw, a trunnion on said other roller member, a set nut on the screw for locking said other member in its adjustments, and means for moving the frame to carry the roller thereof higher than or lower than the fixed roller, one of the rollers of each set being at an oblique position with relation to the other.

In testimony whereof, I affix my signature, in presence of two witnesses.

ALBERT B. WEISSENBORN.
